CARD RETAINING DEVICE

Jack Tendler, Washington, D. C.

Application May 24, 1949, Serial No. 95,020

4 Claims. (Cl. 24—66)

1

This invention relates to a playing card holding or retaining device and more particularly to a card retaining device for holding cards from blowing or inadvertently sliding on a table or the like.

It is an object of this invention to provide a playing card retaining device of the kind to be more particularly described hereinafter which may be economically and attractively formed of metal, plastic or other suitable resilient material engageable with a package of cards for releasably clamping the cards on the base which supports the clamping member.

Another object of this invention is to provide a card retaining device of this kind which is formed in such a manner that the resilient clamping member will exert substantially the same clamping force on the uppermost card of a deck of playing cards and the lowermost card when nearly all of the cards have been withdrawn from the device.

A further object of this invention is to provide a card clamping device for playing cards for securely holding on one side thereof a deck or partial deck of cards, face down, after the hands have been dealt and for holding down the discarded cards, face up, adjacent the face down cards for securely holding against inadvertent movement on the table as from wind or the like.

With the above and other objects in view, my invention consists in the arrangement, combination and details of construction disclosed in the specification and drawings and then more particularly pointed out in the appended claims.

In the drawings:

Figure 1 is a perspective view of a card retaining device constructed according to an embodiment of my invention.

Figure 2 is an end elevation of the card retaining device with the packages of cards removed therefrom.

Figure 3 is a longitudinal section, taken on the line 3—3 of Figure 2.

Figure 4 is an end elevation of a modified form of this invention, including a modified clamping jaw member.

Figure 5 is a fragmentary longitudinal section, partly broken away, taken on the line 5—5 of Figure 4.

Figure 6 is a fragmentary longitudinal section, partly broken away of a second modified form of this invention.

Referring to the drawings, the numeral 10 designates generally a card retaining and clamping device, constructed according to an embodi-

2

ment of my invention, for holding a card or deck of cards in a clamped position, as on a table or the like, for retaining the card or cards against blowing or inadvertently sliding about the table as caused by wind or other exterior causes. The card retaining device 10 is particularly formed for clamping either two decks of cards or one deck of cards and a pile or package of discards, as used in games of pinochle, rummy or the like.

10 The card retaining device 10 is preferably formed of metal, plastic or other suitable inherently resilient material, the card playing device 10 being preferably formed as a substantial integral unit wherein the base and clamping jaws are formed from the same strip of material. The retaining device 10 is formed with a longitudinally extending strip of metal or other material which will normally be disposed in a horizontal plane and defines a base 11 on which 20 a pack or deck of cards C are adapted to be clamping engaged and positioned.

A clamping member 12 is fixed to or, preferably formed integral with, the base 11 and extends upwardly from the base at the center thereof. 25 A second clamping member 14 is also formed integral with the base or secured to the base 11 and one arm of the U-shaped clamping member 12. The clamping member 14 is also U-shaped in configuration having a pair of side arms 15 and 16 connected together at their upper ends by an arcuate bight portion or member 17. The U-shaped clamping member 12 is formed with an upwardly extending side arm 18 and a vertical side arm 19 connected at its upper end to the upper end of the side arm 18 by a resilient bight portion 20. The lower end of the side arm 18, of the clamping member 12 is fixed to or formed integrally with the center portion of the base 11 and the side arm 15 of the clamping member 14 is fixed to or formed integral with the base 11 and the side arm 18 of the other clamping member 12.

The oppositely directed arcuate bight portions or connecting bars 17 and 20 extend outwardly from the center bar 21, formed by the fixed side arms 15 and 18 and extend along the length of the base 11, vertically spaced therefrom.

A clamping jaw 22 is formed on the lower end of the side arm 19 and is adapted to be biased into clamping engagement with the base 11 or with a card or deck of cards supported on the base on one side of the connecting bar or supporting member 21. A similar, inwardly directed arcuate jaw member 24 is formed on the lower end 50 of the other free side arm 16 of the other

clamping member 14 and is also adapted to resiliently bear against the upper side of the base member 11 on the other side of the upstanding member 21. The clamping jaws 22 and 24 are substantially semi-cylindrical in configuration opening upwardly within the clamping members 12 and 14 to provide for the free sliding movement of a card or cards below the clamping jaws and above the base 11 to provide for the clamping engagement of the jaw members 22 and 24 on the upper surface of the cards C.

In the use and operation of the card retaining device 10 after hands of cards have been dealt from the deck the remaining deck is clamped on the device 10 by sliding the remaining cards, face down, under one of the clamping jaws, as the jaw 22. The cards discarded from each hand are slidingly engaged, face up, under the other jaw member 24 whereupon the cards to be further dealt will be supported in the device 10 adjacent the discarded cards and secured against accidental displacement from their arrangement in their packs and against displacement from the table. The arcuate jaw members 22 and 24 provide for the selective sliding of the cards C from between the clamping member 12 and base 11 to be inserted thereafter below the other clamping jaw 24 and above the base 11 on the other side of the upstanding member 21. In other games two decks of cards C will be supported on the clamping member 10, one deck being supported under the clamping member 12 and the other deck being supported under the clamping member 14 whereupon the top card of each of the decks may be slidably removed from under the clamping jaw 22 or 24.

In Figures 4 and 5 of the drawings there is shown a modified form of this invention wherein the clamping jaws are formed in a modified manner. The modified card retaining device 10a is formed in substantially the same manner as the card retaining device 10, described above, and includes a pair of clamping members 12a and 14a, not shown in the drawings which are fixed to and extend upwardly above a base member 11a in substantially the same manner as the card retaining device shown in Figures 1 and 3 of the drawings. The card retaining members 12a and 14a each include a central upstanding supporting member, also not shown in the drawings, and a depending clamping arm or bar 19a extending downwardly from the resilient, upper connecting bar 20a. The lower end of the depending bars or arms 19a are formed with an outwardly bowed, spirally looped, clamping jaw member 22a. The spirally looped clamping jaw member 22a is formed with an outer segmental convolution 25a and an inner convolution 26a. The outer convolution 25a is formed with a central, downwardly opening aperture 27a on the lower side thereof having an axis which is positioned vertically, parallel to the length of the clamping bar 19a. A spherical bearing member 28a is rotatably supported in the circular opening 27a and extends downwardly a slight distance below the surface defined by the outer edge of the outer convolution 25a, at the bottom of the clamping member 12a. The free edge of the inner convolution 26a is adapted to bear against the upper side of the spherical bearing member 28a for retaining the bearing member 28a within the jaw member 22a and extending slightly downwardly below the lower surface of the outer convolution.

In the use and operation of the modified card

retaining member 10a, the cards are handled and positioned in substantially the same manner as the cards are handled in the use of the card retaining member 10, the bearing member 28a providing for the free, intentional, sliding or rotating of the cards engaged between the jaw member 22a and the base 11a for selectively positioning the cards while they are clamped on the card retaining device 10a.

10 In Figure 6 of the drawings, there is shown a second modified form of card retaining member 10b having a horizontal flat base 11b and a central upstanding supporting member 21b. An upwardly bowed connecting bar or bight member 20b is fixed to, or preferably formed integral with the extreme upper end of the connecting bar 21b and an accordion pleated or zigzag foldable clamping arm or member 12b is formed on the lower outer end of the connecting bar 20b. A clamping jaw 22b is formed on the extreme lower end of the zigzag connecting bar 12b and is formed with an outwardly opening hook member or arcuate clamping surface 30 for engagement with the flat surface of a playing card to be clamped between the resilient member 12b and the base 11b. A similar connecting bar 17b is fixed on the upper end of the upwardly extending bar 21b and extends over the base 11b on the opposite side from the connecting bar 20b. 20 A similar accordion foldable resilient member, not shown in the drawings, is fixed to the outer end of the connecting bar 17b for engaging a second pack or deck of cards on the other side of the base 11b, in the same manner as the engagement of the cards in the forms of the invention shown in Figures 1 to 5, inclusive.

In the normal position of the zigzag resilient member 12b, shown in full lines in Figure 6 of the drawings, the cards will be resiliently pressed against the base 11b and as additional cards are placed underneath the clamping jaw 22b, the pleats or connecting arms of the zigzag member 12b will be folded upwardly to the position shown in dotted lines in Figure 6. The formation of the zigzag resilient member 12b provides for the increased tension on the playing cards as the resilient member is folded or reduced in length and the tension on the cards will be slightly reduced as the cards are removed from underneath the clamping jaw 22b. In all other respects the use and operation of the card retaining member 10b is similar to the use and operation of the card retaining members 10 and 10a described above.

I do not mean to confine myself to the exact details of construction herein disclosed, but claim all variations falling within the purview of the appended claims.

What is claimed is:

60 1. A playing card holding device comprising a flat elongated horizontal base for the support thereon of at least two stacks of cards, a first U-shaped resilient clamping member positioned transversely and having its bight facing said base, one of the legs of said member extending between the two stacks of cards, said one leg of said member having its end fixedly secured to said base and forming a backing for one of said stacks of cards, the other of the legs of said member having its end shaped to form a clamping jaw adapted to slidably engage the topmost card of said one stack of cards, a second U-shaped resilient clamping member positioned transversely of and having its bight facing said 70 base, one of the legs of said second member ex-

tending between the two stacks of cards, said one leg of said second member abutting said one leg of the first named member and having its end fixedly secured to said base and forming a backing for the other of said stack of cards, said two fixed legs abutting each other throughout their lengths, the other of the legs of said second member having its end shaped to form a clamping jaw adapted to slidably engage the topmost card of the other of said stacks of cards.

2. A playing card holding device comprising a flat elongated horizontal base for the support thereon of at least two stacks of cards, a first U-shaped resilient clamping member positioned transversely of and having its bight facing said base, one of the legs of said member extending between the two stacks of cards, said one leg of said member having its end fixedly secured to said base and forming a backing for one of said stacks of cards, the other of the legs of said member having its end turned inwardly to form a clamping jaw adapted to slidably engage the topmost card of said one stack of cards, a second U-shaped resilient clamping member positioned transversely of and having its bight facing said base, one of the legs of said second member extending between the two stacks of cards, said one leg of said second member abutting said one leg of the first named member and having its end fixedly secured to said base and forming a backing for the other of said stacks of cards, the two fixed legs abutting each other throughout their lengths, the other of the legs of said second member having its end turned inwardly to form a clamping jaw adapted to slidably engage the topmost card of the other of said stacks of cards.

3. A playing card holding device comprising a flat elongated horizontal base for the support thereon of at least two stacks of cards, a first U-shaped resilient clamping member positioned transversely of and having its bight facing said base, one of the legs of said member extending between the two stacks of cards, said one leg of said member having its end fixedly secured to said base and forming a backing for one of said stacks of cards, the other of the legs of said member having its end formed with a ball supporting loop adapted to slidably engage the topmost card of said one stack of cards, a second U-shaped resilient clamping member positioned transversely of and having its bight facing said base, one of the legs of said second member extending between the two stacks of cards, said one leg of said second member abutting said one leg of the first named member and having

its end fixedly secured to said base and forming a backing for the other of said stacks of cards, said two fixed legs abutting each other throughout their lengths, the other of the legs of said second member having its end formed with a ball supporting loop adapted to slidably engage the topmost card of the other of said stacks of cards.

4. A playing card holding device comprising a flat elongated horizontal base for the support thereon of at least two stacks of cards, a first U-shaped resilient clamping member positioned transversely of and having its bight facing said base, one of the legs of said member extending between the two stacks of cards, said one leg of said member having its end fixedly secured to said base and forming a backing for one of said stacks of cards, the other of the legs of said member adjacent its end being provided with a zigzag foldable portion, the end of the other of the legs of said member being turned outwardly to form a clamping jaw adapted to slidably engage the topmost card of said one stack of cards, a second U-shaped resilient clamping member positioned transversely of and having its bight facing said base, one of the legs of said second member extending between the two stacks of cards, said one leg of said second member abutting said one leg of the first named member and having its end fixedly secured to said base and forming a backing for the other of said stacks of cards, said two fixed legs abutting each other throughout their lengths, the other of the legs of said second member adjacent the free end being provided with a zigzag foldable portion, the end of the other of the legs of said second member being turned outwardly to form a clamping jaw adapted to slidably engage the topmost card of the other of said stacks of cards.
